(57) **CLAIM**

The ornamental design for a water slide, as shown and described.

DESCRIPTION

FIG. 1 is a perspective view showing our new design;

FIG. 2 is a left side view thereof;

FIG. 3 is a right side view thereof;

FIG. 4 is a front elevation view thereof;

FIG. 5 is a rear elevation view thereof;

FIG. 6 is a top plan view thereof; and,

FIG. 7 is a bottom plan elevation view thereof.

The rear and middle portions of the water slide shown in broken lines indicate indeterminate length and form no part of the claimed design. The broken lines showing the connection system on the ends of the pontoons, anchor straps, the air valves form no part of the claimed design.
